(57) **CLAIM**

The ornamental design for a telephone, as shown and described.

DESCRIPTION

FIG. 1 is a top, front and right side perspective view of a telephone;

FIG. 2 is a top view thereof;

FIG. 3 is a front view thereof;

FIG. 4 is a rear view thereof;

FIG. 5 is a right view thereof;

FIG. 6 is a left view thereof; and,

FIG. 7 is a bottom view thereof.

The broken lines are for illustration purposes only and form no part of the claimed design.
